UNITED STATES PATENT OFFICE.

CHARLES W. RENWICK, OF ISABELLA, TENNESSEE, AND NICHOLAS L. HEINZ, OF LA SALLE, ILLINOIS.

ROASTING-FURNACE.

1,080,586.

Specification of Letters Patent.

Patented Dec. 9, 1913.

Application filed November 27, 1911. Serial No. 662,531.

To all whom it may concern:

Be it known that we, CHARLES W. RENWICK, of Isabella, in the county of Polk and State of Tennessee, and NICHOLAS L. HEINZ, of La Salle, in the county of La Salle and State of Illinois, have invented certain new and useful Improvements in Roasting-Furnaces, of which the following is a specification.

Our invention relates to improvements in roasting-furnaces in which a hollow rabble-shaft and hollow rabble-arms are employed in conjunction with means for circulating a cooling liquid through the shaft and arms in order to better enable them to resist the roasting heat of the furnace. A considerable number of devices for this purpose have heretofore been provided and in all of them, so far as we are aware, the entire cooling medium is required to be shut off from the shaft and arms and the heat taken from the furnace in order to repair the rabble apparatus.

It is the object of our improvements, first, to provide simple and efficient means for shutting off the cooling medium from any of the rabble arms without interfering with the circulation through the other portion of the system; and second to afford facilities for readily detaching and replacing the arms individually from the shaft for repairs without interfering materially with the heat of the furnace. We attain these objects by the means illustrated in the accompanying drawings in which—

Figure 1 is a vertical central section through the shaft and arms with a portion in elevation, the dotted lines representing the conventional structure and relation of the roasting furnace therewith. Fig. 2 is a fragmentary view showing an enlarged central vertical section of the shaft at the junction of the arms therewith. Fig. 3 is a horizontal section at the junction of two of the arms with the shaft. Fig. 4 is a detail showing an end or face view of a flanged tubular piece separated from the shaft at the line 4—4 of Fig. 3. Fig. 5 is a detail showing a perspective view of the head of a connecting rod.

Similar numerals marked on the drawings refer to similar parts throughout the several views.

The hollow shaft 7 is provided with a water pipe 8 for introducing water into the shaft. Communication of the hollow of the shaft with the hollow of the rabble-arm 9 is afforded through L-shaped couplings 10 set in perforations through the wall of the shaft at the junction of the arm and standing vertically in the shaft. Said couplings are set with their open end up and in different radial positions to correspond with the several radial positions of the rabble arms and no two of them should fall in the same vertical line in the shaft. When thus arranged each forms a port accessible through the shaft and any of said couplings may be stopped by a rubber plug 11 or any suitable plug, permanently on the end of a rod 12 inserted through the open upper end of said shaft 7, as illustrated in Figs. 1 and 2. The circulation between the water in the shaft and the water in the particular arm, having its port so plugged, will be shut off without interfering with the circulation in the rest of the system. The shaft is provided with flanges 13 (Fig. 3), and 14 designates tubular pieces flanged to match the flanges 13, both being provided with bolt holes (Fig. 4) for securing them together. The outer ends 14^a of said tubular pieces are first made as if closed and then formed with a slot 15 extending clear through the closed end and with side recess 16 extending only part way through, the tubular cavity 17 of said pieces 14 being between the shaft and said slotted end. A connecting rod 18 is provided having an elongated head 18^a which is adapted to pass through the slot 15 and into the tubular cavity 17 where it may be turned a quarter around so as to fall into the recess 16 and become engaged therein. The outer end of said rod is threaded and provided with a nut 18^b for tightening the hollow arm and holding it in its place on the shaft. The outer surface of the tubular piece 14 is formed with a slightly concave seat at a for the inner end of the arm to fit against, and that end is provided with a flange 9^a

between which and the part 14^a, a suitable gasket *g* is applied to make a water tight connection of the arm with the shaft. At the outer end of the arm a brass or suitable washer *b* is applied against the end of the hollow arm and tightened with the nut 18^b and then covered with a cap 19 for making a tight closing at the outer end of the arms.

Our improvements are applicable to any 10 type of roasting furnace, which comprises a series of superimposed hearths having discharge openings placed alternately at the center and periphery and a rotary hollow shaft and hollow rabble arms through or in 15 which a cooling liquid medium, under head in the shaft and arms, is caused to circulate by the action of the heat from the furnace.

The operation is as follows: To remove an arm, insert the plug into the coupling 10, 20 or port, through which the water passes from the shaft to the arm, then remove the cap 19 and nut 18^b. This will loosen the rod 18 and the arm can be taken out bodily. Said rod can also be taken out by pushing it inward until the head passes into the cavity 17, when it may be turned a quarter around and pulled out the head passing through the slot 15. To reattach the arm reverse 25 this process and remove the plug 11 which with its rod 12 can remain within the shaft 30 without interfering with its working while the repair is going on. The arm to be removed should be turned around until accessible through a door of the furnace.

35 What we claim is:—

1. In an ore-roasting furnace of the class described, the combination with a hollow rabble-shaft and hollow rabble-arms of L-shaped tubular ports vertically extended in 40 the shaft and arranged in different radial planes, connections for the arms with the shaft comprising slotted coupling pieces on the shaft in conjunction with rods extended through the arms, and means at the 45 outer ends of the arms for putting the rods under tension in said coupling pieces and for releasing the same.

2. In an ore roasting furnace of the class described, the combination with a hollow 50 rabble-shaft and hollow rabble-arms of tubular pieces 14 mounted on the shaft at its junction with the arms and provided with a slot 15 and recesses 16, a rod 18 having a head adapted to pass through the slot and 55 be engaged by said recesses, and means at the outer end of said rod for putting said rod under tension in said recesses.

3. In an ore roasting furnace of the class described, the combination with a hollow 60 shaft and a series of hollow rabble-arms, of a detachable connection which consists of a tubular piece, part of the shaft, and formed with a slot and recesses at the end adjacent

to the arm and a screw rod, adapted to be inserted through the hollow arm and having a head adapted to pass through said slot and be turned to engage said recesses, as specified.

4. In an ore roasting furnace of the class described, a hollow rabble-shaft provided with horizontal perforations and flanges around said perforations, L-shaped ports having one part threaded in said perforations and another part extended up in the hollow of the shaft, tubular pieces flanged 75 to match the flanges around the shaft-perforations and each provided with a slot and recesses, hollow rabble-arms having their inner ends formed to match the outer ends of said tubular pieces, a rod with a head adapted to pass through said slots and engage in said recesses, and means at the outer end of said rods for affording a bearing against the ends of the arms and putting the rods under tension.

5. In an ore roasting furnace, the combination with a hollow rabble-shaft and hollow rabble-arms of L-shaped tubular ports vertically extended in the shaft and arranged in different radial planes, tubular 90 coupling pieces mounted on the shaft and provided with slots, connecting rods extended through the same, means at the outer ends of the arms for affording access to said rods for putting them under tension in the 95 coupling pieces and for releasing them therefrom, and means for separately plugging said ports through the shaft.

6. In a stirring device for mechanical roasting furnaces for ores and other materials, a shaft, a hollow stirring arm adapted to be fastened to the shaft, a rod arranged within the arm and provided at its inner end with a cross-piece which is adapted to be inserted in a slot in the shaft and to be 105 turned therein to lock the rod to the shaft, and means for fastening the rod to the arm to secure the arm in place on the shaft.

7. In a stirring device for mechanical roasting furnaces for ores and other materials, a shaft, a hollow stirring arm adapted to be fastened to the shaft, a rod arranged within the arm and provided at its inner end with a cross-piece which is adapted to be inserted in a slot in the shaft and to be 115 turned therein to lock the rod to the shaft, stops carried by the shaft to coöperate with the cross-piece to limit the angular position of the rod relatively to the slot, and means for fastening the rod to the arm to secure 120 the arm in place on the shaft.

8. In a stirring device for mechanical roasting furnaces for ores and other materials, a shaft, a hollow stirring arm adapted to be fastened to the shaft and open at its 125 outer end, a rod arranged within the arm

and provided at the inner end with a cross-piece which is adapted to be inserted in a slot in the shaft and to be turned therein to lock the rod to the shaft, a nut within the
5 arm adapted to engage screw threads near the outer end of the rod for the purpose of fastening the rod to the arm to secure the

arm in place on the shaft, and a protecting cover closing the outer end of the arm.
